H. M. ROUSSIE

CAN FOR GASOLINE OR THE LIKE

Filed Oct. 9, 1926

FIG. 1.

Watson E. Coleman
Attorney

Patented May 10, 1927.

UNITED STATES PATENT OFFICE.

HELEN MAE ROUSSIE, OF PROVIDENCE, RHODE ISLAND.

CAN FOR GASOLINE OR THE LIKE.

Application filed October 9, 1926. Serial No. 140,490.

This invention relates to a can for gasoline or the like and it is an object of the invention to provide a can of this kind provided with a normally invisible tube or funnel.

Another object of the invention is to provide a can of this kind particularly designed to contain a reserve supply of gasoline or the like and which is so designed and constructed as to be readily and conveniently stored within a minimum of space in an automobile.

The invention consists in the details of construction and in the combination and arrangement of the several parts of my improved can whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawing, wherein:

Figure 1 is a view in perspective of a can constructed in accordance with an embodiment of my invention;

Figure 2 is a fragmentary sectional view taken substantially on the line 2—2 of Figure 1;

Figure 3 is a detailed sectional view taken substantially on the line 3—3 of Figure 2.

As herein disclosed, my improved can comprises a container C preferably rectangular in form and which has the marginal portions of one face wall extending, as indicated at 1, beyond the side and end walls of the container. One end wall 2 of the container is provided in its central portion with a depression 3 affording a pocket or chamber 4. The inner or bottom wall 5 of this pocket or chamber 4 is provided with a circular opening 6 defined by a depending flange 7. The wall of the opening 6 and the inner wall of the flange 7 are threaded for engagement with the threaded portions 8 at the opposite extremities of the funnel 9.

As herein disclosed, the funnel 9 is cylindrical in form and of desired length and is adapted to have lengthwise movement through the opening 6 hereinbefore referred to. The outward movement of the funnel 9 is limited by the outstanding flange 10 carried by the inner or inserted end of the

funnel 9 while the inward movement of such funnel is limited by the outstanding flange 11 carried by the outer end of the funnel. The inner flange 10 is adapted to have contact with the flange 7 while the flange 11 engages the bottom wall 5 of the pocket or chamber 4.

The outer end portion of the funnel 9 is adapted to be closed by a plug 12 preferably threaded therein and which is provided at one end with an outstanding annular flange 14. This flange 14 at diametrically opposed points is provided with the outstanding pins 15 which, when the plug 12, is inverted, are adapted to be engaged within the openings 16 provided in the flange 11.

The end wall 2 of the container is provided with the guideways 17 for a sliding cover 18 which, when in its full closed position, substantially entirely overlies said end wall 2 as is particularly illustrated in Figures 1 and 2.

Normally, the funnel 9 is housed or confined within the container C proper. When it is desired to pour out the contents of the container, the sliding cover 18 is moved into a position to fully open the pocket or chamber 4 whereupon the plug 12 is removed from the outer end portion of the funnel 9 and then inverted to cause the pins 15 to engage within the openings 16. With this assembly, the plug 12 serves as a wrench whereby the upper or outer threaded engagement between the funnel 9 and the flange 7 is released and upon pulling out the funnel 9 the inner threaded portion 8 is engaged with the flange 7. This operation may also be effected when desired to fill the container. In order to return the funnel 9 to its normal position the operation just stated is reversed.

The opposite faces of the plug 12 are provided with the outstanding wings 19 whereby the requisite turning or rotation of the plug 12 is facilitated.

From the foregoing description it is thought to be obvious that a can constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise

arrangement and formation of the several parts herein shown in carrying out my invention in practice except as hereinafter claimed.

5 I claim:—

As a new article of manufacture, a container having a depression in one of its walls to provide a pocket, the bottom of the pocket having a threaded opening, a funnel adapted 10 to have endwise movement through said opening, the opposite end portions of the funnel having external threads for engagement with the threaded opening, means for limiting the endwise movement of the funnel

in either direction with respect to the bottom wall of the pocket, a removable plug for closing the funnel, means carried by said plug and engageable with the funnel to impart rotation to the funnel to effect or release the threaded engagement between the 20 opposite end portions of the funnel and the bottom wall of the pocket, and a cover co-acting with said wall of the container and disposed over the pocket when in closed position.

In testimony whereof I hereunto affix my signature.

HELEN MAE ROUSSIE.
